UNITED STATES PATENT OFFICE.

ARTHUR R. HAVENER, OF WALTHAM, MASSACHUSETTS, ASSIGNOR TO AMERICAN
LACING HOOK CO., A CORPORATION OF NEW JERSEY.

FEED MECHANISM FOR LACING-HOOK-SETTING MACHINES.

1,078,350.

Specification of Letters Patent.

Patented Nov. 11, 1913.

Application filed May 22, 1913. Serial No. 769,135.

To all whom it may concern:

Be it known that I, ARTHUR R. HAVENER, a citizen of the United States, residing at Waltham, in the county of Middlesex and 5 State of Massachusetts, have invented new and useful Improvements in Feed Mechanism for Lacing-Hook-Setting Machines, of which the following is a specification.

This invention relates to an improvement 10 in feeding mechanisms for lacing hook setting machines, the same being particularly adapted for use in connection with machines of the class shown and described in the United States patent issued to me November 29, 1910, for machine for setting lacing hooks, No. 977,090, to which reference may be had.

The object of this invention is to provide 20 a feeding mechanism in which the upper of the shoe is first punched and then fed forward to the lacing hook setting mechanism, the punch being provided with an annular clenching surface, all as set forth in said Letters Patent. It is very essential in a 25 machine of this class that the mechanism whereby the upper of the shoe is punched and fed should be such that the punch will be firmly and accurately held in position during the punching and feeding operations, whether said punch is used in a machine 30 wherein a female die co-operates with a male punch during the punching operation, said punch being subsequently utilized to feed the upper of the shoe forward 35 into proper position with a lacing hook set therein, or whether said male punch co-operates with a plate during the punching operation and subsequently is moved laterally thereof to feed the upper along the 40 upper surface of said plate after the setting of the lacing hook has taken place. It is well known to those skilled in the art that the accurate location of the male punch 45 relatively to the female die or plate co-operating therewith must be maintained in order to secure practical results in the punching and feeding operations.

The object of this invention, therefore, is 50 to so hold and sustain a punch during the punching and feeding operation that the relation of the punch to the die shall be accurately maintained. Prior to this invention it has been customary to guide the punch holder by means of guide rods located 55 one above the other. The objection to this

construction resides in the fact that there is liability of the punch tipping slightly on its supporting guide rods laterally and this destroys the accurate relation of the punch to the part co-operating therewith, whether 60 it be a female punch or a die plate.

It is also very desirable in machines of this class to have the punch holder accurately and firmly supported during all its operations of punching and feeding, and to 65 make said holder light in order that it may be fed with rapidity without jarring the machine. In automatic machines of the class to which this invention relates the punching and feeding operation is very 70 rapid, being at a rate of three hundred and fifty to five hundred rotations or complete operations per minute.

It is, therefore, the object of this invention 75 to provide a holder which, while supported firmly during all its different operations, shall be light and durable in its construction.

To these ends the invention consists in the 80 combination and arrangement of parts set forth in the following specification and particularly pointed out in the claims thereof.

Referring to the drawings: Figure 1 is a 85 front elevation, partly broken away and shown in section, of my improved feeding mechanism shown in connection with a lacing hook setting machine. Fig. 2 is a sectional elevation taken on line 2-2 of Fig. 1 illustrating a punch holder and the slide by which a vertical reciprocatory motion is 90 imparted thereto. Fig. 3 is a sectional plan taken on line 3-3 of Fig. 1, illustrating the punch holder and the mechanism by which vertical and horizontal reciprocatory movements are imparted thereto. Fig. 4 is 95 a detail sectional plan taken on the irregular line 4-4 of Fig. 1 illustrating the portion of the mechanism by which a horizontal reciprocatory movement is imparted to the punch holder and punch.

Like numerals refer to like parts throughout the several views of the drawings.

In the drawings 5 is the frame of the machine.

6 is a vertically movable slide to the rear side of which is attached a block 7 having a curved slot 8 provided in its rear face in which is located a sliding block 9 mounted on a crank-pin 10 fast to the crank 11, said crank being fastened to a shaft 12 rotatably 105 110

mounted in suitable bearings 13 in the frame of said machine. A rocking motion is imparted to the shaft 12 by a crank 14 fast to the rear end of said shaft and connected by a rod 15 to a rocker plate 16 pivoted at 17 to the frame 5.

The rocker plate 16 has two cam rolls 18 and 19 journaled thereon and bearing against opposite sides, respectively, of the cams 20 and 20'. The cams 20 and 20' are fastened to the main driving shaft 21 of the machine, said driving shaft being rotatably mounted in suitable bearings on said frame 5. By means of this mechanism a rocking motion 15 is imparted to the rocker plate 16 and, through the rod 15, a rocking motion is imparted to the rocker arm 14, the shaft 12 and the arm 11, which results in a movement of the sliding block 9 longitudinally of the slot 20 8 in the plate 7 and a resultant reciprocatory movement is imparted to the slide 6.

The slide 6 is provided at its lower end (see Fig. 2) with lateral projections 22 and 23, in which are clamped a pair of guide rods 24 and 25. Said guide rods are preferably tubular in form in order to render the device light, and are located on opposite sides, respectively of the slide 6, with their median longitudinal lines lying in substantially the same horizontal plane, said slide 6 being suitably guided in bearings 26 and 27 provided in the frame 5.

A punch 28 is fastened to a holder 29 which is mounted to slide horizontally on 35 the guide rods 24 and 25. The guide rods 24 and 25 are clamped to the lateral projections or ears 22 and 23 by means of clamp screws 30 and 31, respectively, said clamp screws having screw-threaded engagement 40 with ears 32 and 33 and rotatable engagement with ears 34 and 35, said ears 32 and 34 and 33 and 35 being obtained by splitting the lateral projections 22 and 23 longitudinally and horizontally thereof.

45 The holder 29 has two bosses 36 and 37 thereon adapted to slide on the guide rod 24 and two bosses 38 and 39 thereon adapted to slide on the guide rod 25, so that said holder is firmly supported at four points 50 upon said guide rods 24 and 25. The bosses 36 and 37, it will be noted, are located on the opposite side of the slide 6 from that upon which the bosses 38 and 39 are located.

A reciprocatory movement is imparted to 55 the holder 29 by an arm 40 fast to a vertical rock-shaft 41. Said arm is bifurcated at its free end and has fastened thereto a rod 42 which passes through a sliding block 43 located in a slot 44 on the holder 29. The 60 arm 40 is clamped to a vertical rock-shaft 41 by means of a clamp screw 45. The rock-shaft 41 is mounted in suitable bearings 46 and 47 on the frame 5, and to the lower end of said rock-shaft is fastened an arm 48 65 provided upon its upper face with index

graduations 49. A link 50 is pivotally connected by a pin 51 to the arm 48, said pin being adapted to engage teeth or corrugations 52 provided on one side of a slot 53 in said arm. Said pin is withdrawn from engagement with said teeth by a lever 54 which is pivoted at 55 to the under side of the arm 48 (see Fig. 1). A spring 56 holds the pin 51 in engagement with the teeth 52 and when it is desired to disengage said pin 51 from said teeth, the lever 54 is raised at its outer end, the pin 51 thus being depressed and drawn out of contact with the teeth 52. At this time the link 50 can be rocked, by means of the handle 57, upon its pivot 58 to any desired location and said location indicated by means of an index finger 59 fast to said link. A reciprocatory motion is imparted to the arm 48 and to the shaft 41 by means of a cam slide 60 to which said link is pivoted at 58. Said cam slide is mounted upon rods 61 and 62 fast to the frame of the machine (see Fig. 1), and upon said cam slide two rolls 63 and 64 are rotatably mounted, said rolls being located on opposite sides, respectively, of two cams 65 and 65' which are fastened to the main driving shaft 21, so that as said main driving shaft rotates the slide 60 is reciprocated and a reciprocatory motion is thus imparted to the link 50 and by it a rocking motion imparted to the arm 48, rock-shaft 41 and arm 40, whereby a reciprocatory motion is imparted to the holder 29 and the punch 28 fast thereto.

The general operation of the mechanism hereinbefore specifically described is as follows: A rocking motion is imparted to the shaft 12 through the cranks 11 and 14, connecting rod 15 and cam 20 to move the slide 6 downwardly and drive the punch 28 through the upper, which is at that time located upon a work supporting plate 66. The upper is held in position at this time by a presser foot 67 in a manner described in said Letters Patent. The punch 28, with its holder 29, is forced downwardly by the slide 66 to punch a hole in the leather, at this time co-operating with a suitable female die or plate, such for instance, as illustrated and described in said Letters Patent. The lacing hook is then set in the upper and a lateral motion is then imparted to the punch through its holder 29 and the connections hereinbefore described by which a horizontal movement is imparted to said holder and said holder slides along the guide rods 24 and 25, thus feeding the upper along the work-support 66. At the end of the feeding movement of the upper the slide 6 is actuated to withdraw the punch from said upper, and after said punch has been so withdrawn, it is moved toward the right (Fig. 1) by its holder 29 and the connections by which a horizontal movement is imparted 130

to said holder, hereinbefore described, thus bringing the punch and its holder back to the position illustrated in Fig. 1, in readiness to punch another hole, feed the upper, 5 and have another lacing hook set therein, as fully described and illustrated in said Letters Patent.

Having thus described my invention, what I claim and desire by Letters Patent 10 to secure is:

1. A lacing hook setting machine having, in combination, a work holder, a vertically movable slide, mechanism adapted to impart a reciprocatory motion to said slide, a pair 15 of horizontally disposed guide rods fast to the lower end of said slide and on opposite sides thereof, respectively, a horizontally movable holder mounted to slide on said guide rods, mechanism adapted to impart a reciprocatory motion to said holder, a punch 20 fast to said holder and means adapted to coöperate with said punch to punch a hole in an upper on said work holder, whereby said upper may be punched and fed along 25 said work holder.

2. A lacing hook setting machine having, in combination, a work holder, a vertically movable slide, mechanism adapted to impart a reciprocatory motion to said slide, a pair 30 of horizontally disposed guide rods fast to the lower end of said slide and on opposite sides thereof, respectively, a horizontally movable holder mounted to slide on said guide rods, a vertical shaft, mechanism 35 adapted to impart a rocking movement to said shaft, an arm fast to the upper end thereof and means connecting said arm to said holder intermediate said guide rods, a punch fast to said holder and means adapted 40 to coöperate with said punch to punch a hole in an upper on said work holder, whereby said upper may be punched and fed along said work holder.

3. A lacing hook setting machine having, in combination, a work holder, a verti- 45

cally movable slide, mechanism adapted to impart a reciprocatory motion to said slide, a pair of horizontally disposed guide rods fast to the lower end of said slide and on opposite sides thereof, respectively, a horizontally movable holder mounted to slide on said guide rods, a vertical shaft, an arm fast to the lower end of said shaft with index graduations thereon and mechanism, including a link, adjustably fastened to said arm, said mechanism adapted to impart a rocking movement to said shaft, an index fast to said link adjacent to said graduations, an arm fast to the upper end of said shaft, means connecting said arm to said holder intermediate said guide rods, a punch fast to said holder and means adapted to coöperate with said punch to punch a hole in an upper on said work holder, whereby said upper may be punched and 65 fed along said work holder.

4. A lacing hook setting machine having, in combination, a work holder, a vertically movable slide, mechanism adapted to impart a reciprocatory motion to said slide, 70 a pair of horizontally disposed guide rods fast to the lower end of said slide and on opposite sides thereof, respectively, with their longitudinal median lines lying substantially in the same horizontal plane, a horizontally movable holder mounted to slide on said guide rods, mechanism adapted to impart a reciprocatory motion to said holder, a punch fast to said holder and means adapted to coöperate with said punch 75 to punch a hole in an upper on said work holder, whereby said upper may be punched and fed along said work holder.

In testimony whereof I have hereunto set my hand in presence of two subscribing witnesses.

ARTHUR R. HAVENER.
